ELECTROMECHANICAL OSCILLATOR

Noel Deisch, Washington, D. C.

Application April 16, 1928. Serial No. 270,546

10 Claims. (Cl. 250—36)

My invention relates to electromechanical oscillators, and has special reference to means of drive therefor.

The principal object of the invention, generally stated, is to provide an electromechanical oscillator adapted to function either as an oscillation generator or as a resonator, in which a non-piezoelectric and non-magnetic body, whether insulating or conducting in nature, 10 may be used as the oscillating member.

Another object of the invention is to provide an electromechanical oscillator in which the driving force is applied electrostatically rather than electromagnetically.

15 Another object of the invention is to provide an electrostatically driven electromechanical oscillator bearing armatures through one or both of which the driving force is applied, or from either of which an electrical frequency may be obtained that may be used indirectly to effect the 20 drive of the rod, or to control an associated circuit.

Another object of the invention is to provide, in an oscillator having electrostatically operative armatures, means whereby said armatures 25 may be electrically charged to a desired potential.

Another object of the invention is to provide a circuit arrangement suitable for driving an oscillator electrostatically.

30 Another object of the invention is to provide, in an electromechanical oscillator driving system, means to set the oscillating member into oscillation from a condition of rest.

Developments in physics and especially in the 35 electrical arts have brought a demand for a source of timing impulses of rigorous regularity, suitable for use in frequency control and frequency measurement, and, in general, as a reference standard in any timing operation.

40 As is well known, piezoelectric oscillators have been extensively used in this application, but these oscillators are subject to various disadvantages;—their preparation is costly and tedious, due to the fact that they must be cut 45 from natural crystals, their dimensions are limited by the size of available crystals, and their form is limited to that of a plate or slab, this last fact making it difficult in certain applications to mount the oscillators to the best advantage. Finally, the relatively high thermal dilatation of crystal quartz brings a higher temperature 50 change of frequency than is desirable.

By the present invention it becomes possible to employ any preferred elastic material in the 55 construction of an oscillator, as also to use shapes

better fitted to reduce harmonic vibrations and parasitic damping, these combined advantages making possible the attainment of a much higher constancy of frequency. As respects material, vitreous silica, for example, which represents 60 the closest approach among known materials to the ideal elastic substance, possessing both the lowest elastic hysteresis and the lowest temperature coefficient of dilatation of any material known, may be used with great advantage. 65 Where cost is an important factor, certain glasses whose properties approach those of vitreous silica, such, in general, as borosilicate glasses of high silica content.

The oscillator in its preferred form consists of 70 an elastic rod supported at its nodal point and oscillating freely along its longitudinal axis at its lowest natural frequency. The oscillation of the rod is initiated and sustained through the alternating electrostatic attraction exerted on 75 an armature or armatures preferably attached to the ends of the rod, by which energy is imparted to the rod at each oscillation. Since the frequency of vibration is in most cases exceedingly high, corresponding to a high mean velocity of 80 approach and recession of the armatures, and since on the other hand the losses in the rod will usually be very small, the value of the force that must be brought to act on the electrodes to sustain the oscillations is correspondingly small. 85

In the drawing:

Fig. 1 is a diagram of an oscillator incorporated in a circuit such as may be used in effecting its drive.

Fig. 2 is an elevation of a rod-shaped oscillator 90 and mounting, and shows a method of supporting the oscillator and its field electrodes.

Fig. 3 is a top plan view of Fig. 2.

Fig. 4 is a horizontal section on the line 4, 4 95 of Fig. 2.

Referring now to Figs. 2, 3, and 4, there is shown as an illustrative form of the invention a preferably cylindrical rod 33, supported at its nodal point by appropriate means, as by the clamp 34. At either end of the rod 33 are armatures 30, which may consist of thin conducting plates formed on the ends of the rod by the chemical deposition on the latter of a layer of metallic silver or by the cathodic deposition of a thin film of any suitable metal. One or more conducting strips 32 make electrical connection between the armatures 30 and the lead 35 through the clamp 34. Adjacent the armatures 30, and usually separated from them by only a very slight distance (e. g., circa 0.02 cm) are the field 105

electrodes 29, forming part of the yokes 28. Each of the armatures 30 with its associated field electrode 29 constitutes an electrostatic couple, the two elements of which are held in definite relation by means of a suitable supporting structure, such as the spacer rods 26, the last being held securely in the central clamp 34 and the yokes 28, as shown. The armatures 30 are electrically isolated from the field electrodes 29, as by the 10 insulating bushings 27.

It will be obvious that if the electrodes 29 be connected, as through the leads 31, to a suitable coacting circuit producing electrical oscillations, the oscillating potential active on the field electrodes 29 will cause these to become periodically charged, an opposite charge being at the same time periodically induced in the armatures 30. The armatures 30 will hence be periodically attracted. If the period of the oscillating force 20 coincide with the natural period of the rod, the rod will be thrown into oscillation. It is thus apparent that the rod may be applied as a frequency tester, controller, or stabilizer to an independent circuit, acting in these several cases as a resonator.

When it is desired to employ the device as an oscillation generator the rod, as is usual in the oscillator art, will be coupled into a properly arranged coacting driving circuit, the oscillating rod 30 reacting on the associated circuit in such a way as to control the frequency of the circuit, constraining this frequency to conform precisely to the frequency of the rod. In the circuit shown by way of illustration in Fig. 1 the driving energy 35 to the rod 21, supported at 22, is shown as applied through the armature 19, whereas the armature 23, in association with the field electrode 24, serves to control the frequency of the circuit in a manner to be described. The armatures 19, 40 23, are connected through conducting strips 20 and the lead 11 to one pole of a battery 10, by which means they receive a permanent electric charge. The driving field electrode 18 has connection through the lead 13 to the secondary 15 of the transformer 14 and to ground, whereas the electrode 24 normally has connection through the lead 12 to the grid 9 of the triode 8. The 45 plate-filament circuit of the triode 8 in the position of the switch 6 shown in full lines, comprises the battery 10 and the primary 16 of the transformer 14.

Considering now the controlling action of the mechanical oscillator on the circuit, it is evident that the armature 23 and its field electrode 24 50 form a condenser whose capacity varies with the distance separating their adjacent plates. One plate of this condenser (the armature 23 in the present example) is charged to a given potential by the battery 10, as above noted. Battery 10 is 55 connected across the filament and plate of tube 8, as shown. An electron discharge takes place through tube 8, resulting in a difference of potential being set up between the filament and grid thereof, which potential is communicated to plate 23 through leads 11 and 20 and to plate 24 through lead 12. With the rod in oscillation the charge active on the field electrode 24 will thus 60 increase as the armature 23 approaches electrode 24 and will decrease as the armature recedes 65 from electrode 24, the harmonic wave of potential thus produced in electrode 24 being communicated to the conductor 12 and through it to the grid 9 of the triode 8. An amplified pulsating current is thus produced in the filament-plate 70 circuit of the triode 8 which, flowing through the

primary 16 of the transformer 14 induces an alternating potential in the secondary 15 of said transformer. This alternating potential acts through the field electrode 18 on the armature 19 (which, as before stated, is charged to a constant potential of one sign) to cause an alternate attraction and repulsion in the same, thus serving to drive the rod. The potential of the battery 10 is communicated to plates 18 and 19 partly by direct metallic conduction and partly through electrostatic or condenser action, resulting in the flow of a displacement current. The circuit comprises plate 19, leads 20 and 11, battery 10, coils 16 and 15 of transformer 14, lead 13 and plate 18. Mutual electrostatic action between coils 16 and 15 causes a displacement current to flow in the lead 13, placing plate 18 at a different potential from plate 19. An amount of lag is introduced into the electrical oscillations in the course of their passage through the transformer 14 which the purposes of the arrangement make desirable.

The "starting" i. e., the initiation of oscillations in the rod is accomplished through an accessory component of the circuit, which associated component may be switched in when required. The driving armature 19 of the rod is thereupon supplied with a pulsating current of approximately the same frequency as the natural frequency of the rod, and this frequency is then varied until it attains the natural frequency of the rod. When the applied frequency coincides with the natural frequency of the rod, the latter is set into oscillation, and the electrical connections may then be shifted so as to allow the rod to operate automatically.

More particularly, to bring the auxiliary circuit into operation the bi-pole switch 6 is shifted to the position shown in dotted lines at 7. The grid 9 of the triode 8 is thus connected through the secondary 2 of the variable inductance coil 1 having the movable core 3 and to ground, the primary winding 4 of the coil 1 being at the same time put into series with the primary winding 16 of the transformer 14, and included in the filament-plate circuit of the triode 8. With this arrangement current is fed back from the coil 2 to the grid of the amplifying tube 8 in the way usual in this type of oscillating circuit. The circuit will begin to oscillate as soon as the double-throw switch is moved to the position shown in dotted lines at 7. The constants of the coil 1 and the attached circuit are such that with the movable core 3 inserted the electrical oscillations generated are of lower frequency than the natural period of the rod. The frequency of oscillation is then raised by slowly withdrawing the core 3 until the rod begins to oscillate, which condition will be indicated by a fall of voltage registered by the voltmeter 5. The switch 6 will then be thrown to the position in which it is shown in full lines, whereupon the rod will continue in oscillation automatically.

While I have described my invention in detail with respect to the preferred form thereof, I do not desire to be limited to the form described, since many changes or modifications may be made in this form without departing from the spirit and scope of my invention, and I desire to cover all modifications and forms coming within the scope of the appended claims.

I claim:

- An oscillator, comprising a body of vitreous material of low elastic hysteresis and low temperature coefficient, armatures attached at antinodal points to said body, means whereby

- 5 said armatures may be given an electric charge, electrodes held in definite relation to said armatures, and means to bring an electric charge of periodically varying value and sign to act in 5 $n-1$ of said electrodes to constrain said body to oscillate.
- 10 2. An oscillator, comprising a rod of vitreous material of low elastic hysteresis and low temperature coefficient supported substantially at its 10 nodal point, armatures attached at non-nodal points to said rod, electrodes held contiguous to said armatures, and a source of oscillating potential to supply energy to drive said rod.
- 15 3. An oscillator, comprising a rod of vitreous material of low elastic hysteresis and low temperature coefficient supported at its nodal point, 15 conducting plates attached at antinodes to said rod, means to connect said conducting plates to a source of potential, other conducting plates 20 held in close approximation to said electrodes, and an oscillation generator to supply energy to 20 drive said rod.
- 25 4. An oscillator, comprising a rod of vitreous material of low elastic hysteresis and low temperature coefficient supported at its nodal point, 25 flat conducting plates, here called armatures, attached at opposite ends of said rod, conductors extending along said rod to connect said armatures to a source of electric potential, conducting 30 plates, here called field pieces, held in close proximity to said armatures, an oscillation generator 30 to supply energy to $n-1$ of said field pieces to drive said rod, and a relay system coupled to one 35 of said field pieces to control said frequency generator.
- 35 5. In electromechanical oscillators, a vitreous elastic body of low temperature coefficient, means 35 to support said body at a point allowing symmetrical longitudinal oscillation thereof, conducting 40 armatures secured to said body, conducting leads 40 to connect said armatures to a source of electrical energy, electrodes held in proximity to said armatures, conducting leads to connect said electrodes to a source of electrical energy, and structural 45 means coupling said oscillator supporting means and said electrodes to hold said armatures and said electrodes in a desired spatial relation.
- 45 6. In an electromechanical oscillator electrically coupled to an electrical oscillation generator supplying driving energy to said oscillator, and including means normally controlled by said oscillator for controlling the frequency of the oscillations produced by said oscillation generator; 50 means for producing oscillations in said oscillation generator independently of the controlling action of said oscillator, and means for bringing the frequency of these independently produced oscillations to the natural frequency of said oscillator to bring said oscillator into oscillation from a state of rest.
- 55 7. In an electromechanical oscillator electrically coupled to a circuit supplying driving energy to said oscillator, and including means by which the frequency of the output of said circuit is 55 during the normal operation of said oscillator controlled by said oscillator; means to alter the electrical characteristics of said circuit to make said circuit self-oscillating, and means to bring the natural electrical period of said self-oscillating circuit to substantial coincidence with the natural mechanical period of said oscillator.
- 60 8. An electromechanical oscillator, comprising a rod of silica, a frame for supporting said rod 60 at its middle, metal plates mounted on the ends of said rod, metallic yokes connecting the ends of the frame and spaced in inductive relation to said plates, and means for connecting said plates and said yokes to a source of periodically varying 65 electric force.
- 65 9. An electromechanical oscillator, comprising a silica rod having metal plates mounted on its ends, a frame including side bars, middle and end yokes, the middle yoke being clamped to the mid- 70 section of said rod and the end yokes in close proximity to said plates and insulated from said side bars, a conductor connecting said plates to the middle yoke and means for connecting the several yokes to a source of periodically varying 75 electric force.
- 75 10. A body of vitreous material of low elastic hysteresis and low temperature coefficient capable of oscillation, armatures attached to said body, and means to act on one of said armatures 80 electrostatically to cause said body to oscillate.
